Primary Examiner — John Windmuller(57) **CLAIM**

The ornamental design for a television antenna with stand, as shown and described.

DESCRIPTION

FIG. 1 is a front perspective view of a television antenna with stand showing my new design;

FIG. 2 is a rear perspective view thereof;

FIG. 3 is a side elevation view thereof, the opposite side elevation view being a mirror image thereof;

FIG. 4 is a top plan view thereof;

FIG. 5 is a bottom plan view thereof;

FIG. 6 is a rear, side perspective view thereof;

FIG. 7 is a front, side perspective view thereof; and,

FIG. 8 is a front elevation view thereof, shown with the stand in a flattened position.
